UNITED STATES PATENT OFFICE

EARLE S. MACPHERSON, OF DETROIT, MICHIGAN, ASSIGNOR TO HUPP MOTOR CAR CORPORATION, OF DETROIT, MICHIGAN, A CORPORATION OF VIRGINIA

CRANK-CASE VENTILATOR

Application filed November 15, 1926. Serial No. 148,569.

This invention relates to crank case ventilators and more especially to means for ventilating the crank case of internal combustion engines and the like.

5 It is now generally customary, in the manufacture of internal combustion engines, to provide a crank case breather in conjunction with the oil filler spout or inlet. However, such breather openings do not adequately 10 ventilate the crank case principally because no provision is made for inducing or promoting circulation of air.

It is therefore, one of the primary objects 15 of this invention to provide a crank case ventilating means wherein air is forcibly and positively circulated through the crank case while the engine is running. For this purpose the herein described apparatus contemplates the provision of a vacuum inducing 20 means connected to the crank case and a source of air supply also connected to the crank case. While the air inlet is preferably auxiliary to the customary breather opening, nevertheless, it will be obvious as this description 25 proceeds that the breather opening may be employed for supplying an amount of air to the crank case sufficient to dissipate the effects in the vacuum induced therein.

Among the advantages obtainable from a 30 thorough ventilation of the crank case is that when the engine is operated in cold weather this ventilation prevents the formation of moisture and thus practically eliminates the corrosion of the bright metal parts by moisture and by acid.

The several objects, advantages and novel 35 details of construction of this invention will be made more apparent as this description proceeds especially when considered in connection with the accompanying drawings wherein:

Figure 1, is a sectional elevational view illustrating fragmentarily a crank case and the appurtenances of an internal combustion 45 engine with my invention associated therewith and,

Figure 2, is a front elevation partly in vertical section of the structure illustrated in Figure 1.

50 Referring now more particularly to the

drawings wherein like reference characters indicate like parts it will be noted that there is illustrated fragmentarily the wall 10 of the crank case of an internal combustion engine to which is connected the oil filler spout 11 provided with the customary removable cover 12 for closing the open end thereof. This cover 12 is provided with breather openings 13.

The reference character 14 indicates the exhaust manifold of the internal combustion engine and 15 a sleeve-like coupling member inserted therein. This sleeve provides means for mounting and positioning within the exhaust pipe and in the path of the exhaust gases the outlet end of an ejector pipe 16. For convenience in manufacture and assembly the outlet end of the ejector pipe may be in the form of an elbow 17 which is secured to and carried by the sleeve 15. The open end 18 thereof extends in the direction of the flow of the exhaust gases so that when the engine is running a vacuum is created in the ejector pipe 16 for the purpose of inducing a partial vacuum in the crank case as will appear more fully hereinafter.

The other end of the ejector pipe is connected by means of the union 19 to the wall 20 of a chamber 21 communicating with the interior of the crank case. While it is obvious that the inlet end of the ejector pipe might be just as readily connected to the crank case it has been found that it is more convenient for manufacturing and assembly purposes to provide the auxiliary chamber 21. The inlet end of the ejector pipe is protected by means of a baffle 22 which will prevent oil in any appreciable quantity being drawn through this ejector pipe. The end of the pipe is further protected by means of a screen 23 which will prevent the entrance of foreign matter which would tend to clog up the pipe.

In Figure 2 the reference character 24 indicates generally the carburetor of the internal combustion engine and 25 an air cleaner which constitutes the air inlet or supply for the carburetor. A conduit 26 connects air cleaner 25 to carburetor 24 and communicating with this source of air is a conduit 27.

connected to an opening 28 formed in the 5 filler spout 11. Thus a portion of the air flowing to the carburetor may pass through conduit 27, opening 28 and filler spout 11 and into the crank case to supply the quantity of air needed to dissipate or offset the vacuum induced by the ejector pipe 16. It has been found to be efficient and practical to form the 10 conduit 26 and conduit 27 of an integral casting the conduit 27 constituting a lateral extension of the sleeve-like conduit 26 as by such a construction this unit may be connected to the filler spout 11 by means of a bolt 29 in a manner most clearly illustrated in 15 Figure 1.

With the herein described construction a positive source of circulation of air is provided through the crank case during those periods that the engine is running. The flow 20 of exhaust gas through the exhaust pipes 14 will create a vacuum in the ejector pipe 16 which will draw air from the crank case as suggested by the arrows and as a consequence of the connection between the crank 25 case and the carburetor air inlet the air thus withdrawn from the crank case will be supplied from this air source. It is evident, however, that while the preferred embodiment of the invention herein described 30 contemplates an auxiliary source of air that the air withdrawn from the crank case may, when desired, be supplied through the customary breather opening.

It will also be evident to those skilled in 35 this art that various changes may be resorted to in the details of construction and the arrangement and association of parts as may be found necessary or expedient and to this end reservation is made to make such changes 40 as may come within the purview of the accompanying claims.

What I claim as my invention is:—

1. In combination, a crank case having an oil filler spout, an exhaust manifold, an air 45 supply and ventilating means for said crank case including means connecting said crank case to said manifold for inducing a vacuum in the former and means connecting said air supply to said filler spout.

50 2. In combination, an exhaust manifold, a carburetor air supply conduit, a crank case provided with an oil filler spout, an ejector pipe extending into said exhaust manifold and connected to said crank case for inducing 55 a vacuum in the latter and means connecting said air supply conduit to said filler spout for supplying air to said crank case to dissipate said vacuum.

60 3. A crank case ventilator comprising in combination, a crank case provided with an oil filler spout, an exhaust manifold, a carburetor air inlet, a chamber connected to said crank case, a pipe extending from said chamber to said exhaust pipe with the open end 65 thereof disposed in the direction of flow of

the exhaust gases to cause a partial vacuum in said crank case, a baffle protecting the end of said pipe connected to said chamber and means connecting said filler spout to said air inlet for supplying air to said crank case to 70 dissipate said vacuum.

4. In combination a carburetor, an air filter for the carburetor, a crank case, means for inducing a vacuum in the crank case, an oil filler spout for the crank case, and a conduit connecting the air filter and the carburetor; the said conduit having an upwardly extending portion opening into the said oil 75 filler spout.

5. In combination, a crank case having an 80 oil filler spout, means for creating a vacuum in the crank case, and a carburetor air supply conduit having a laterally extending branch communicating with the oil filler spout.

6. In combination a crank case, an oil 85 filler spout for said crank case, a carburetor, an air filter for the carburetor, a connection between the air filter and the carburetor, the said connection having a portion communicating with the said oil filler spout for conducting air from said filter to said filler spout, an exhaust manifold, a chamber connected to said crank case, a pipe extending from said chamber to said exhaust manifold 90 with the open end thereof disposed in the direction of flow of the exhaust gases through said manifold to cause a partial vacuum in said crank case, and a baffle protecting the end of said pipe, said baffle being connected 95 to said chamber.

In testimony whereof I affix my signature.
EARLE S. MacPHERSON.
